UNITED STATES PATENT OFFICE

132,640

DESIGN FOR A MICROMETER CALIPER

Clarence T. Rottler, Seattle, Wash.

Application September 15, 1941, Serial No. 103,356

Term of patent 14 years

To all whom it may concern:

Be it known that I, Clarence T. Rottler, a citizen of the United States of America, residing at Seattle, in the county of King and State of Washington, have invented a new, original, and ornamental Design for a Micrometer Caliper, of which the following is a specification, reference being had to the accompanying drawing, forming part thereof.

Figure 1 is a side elevational view of a micrometer caliper, and Figure 2 is an edge elevational view of the same, showing my new design.

The characteristic features of my design reside in the portions shown in full lines.

I claim:

The ornamental design for a micrometer caliper, substantially as shown and described.

CLARENCE T. ROTTLER.
